1**2,758,345****ALL PURPOSE WINDOW**

Walter L. White, Miami, Fla., assignor to Cadillac Window Corp., a corporation of Florida

Application August 8, 1952, Serial No. 303,333

2 Claims. (Cl. 20—62)

This invention relates to an all purpose window, and more particularly, has reference to a window including a pair of slotted, symmetrically aligned assemblies adapted to be selectively controlled in a manner to increase the versatility of the window, above that of more conventional windows.

As presently designed, windows present certain disadvantages, and notable among these is a lack of versatility. Thus, an ordinary window, considered per se, may be opened or closed for controlling the ventilation of a building structure, and will admit light to the interior of the structure. However, if it is desired that the window not only control ventilation, but also the quantity of light to be admitted to the interior of the building structure, it is necessary that an extraneous or collateral aid be provided, in the form of a venetian blind, shade, or the like. In such an instance, a person or firm other than the window manufacturer or installer must be called, and the light controlling device is, in most instances, used independently of the window itself.

Additionally, a conventional window is so constructed as to require, in many instances, the addition of a storm sash which, like the venetian blind, is a device separate and apart from the window itself. The storm sash, in some forms thereof, is of a semi-permanent nature requiring its manual erection or removal at different times of the year. In other instances, the storm sash is so designed as to permit it to be permanently mounted upon the window frame, the latter type of sash requiring, however, that portions of the sash be mechanically adjusted to an inoperative position when they are not to be used.

Still further, a conventional window will generally require the use of a surrounding frame constructed either of precast concrete, or formed as a wood buck. This element of the window must generally be made by a general contractor or subcontractor, or someone other than the person or persons installing or manufacturing the window itself.

Still further, it is believed to be a disadvantage of conventional window construction that the use of the above-mentioned aids will, in many instances, detract from the architectural attractiveness of the building structure, this being true with respect to both the interior and the exterior of said structure.

Another disadvantage which has been noted in conventional windows is inherent in the use of a plurality of moving, engaged parts, which parts when adjusted relative to one another create friction, thereby causing wear, malfunctioning, and increased repair and maintenance costs.

In view of the above, the broad object of the present invention is to provide a window construction wherein, in a single, unitary assembly, there will be provided an arrangement which will eliminate the necessity of different tradespeople constructing or installing different parts of the window, said assembly being at the same time so designed as to permit its use both as a ventilating and a light controlling device.

2

Another object of importance is to provide a window of the character referred to wherein the ventilation and light control characteristics can be brought into play independently of or in conjunction with one another, as desired.

Still another object of importance is to provide a window assembly of the type stated in which friction producing parts will be reduced to a minimum, thus to provide for a proportionate decrease in repair and maintenance costs.

Yet another object of the present invention is to provide a window construction as stated which will eliminate the necessity of venetian blinds, storm sash, or the like, the window formed in accordance with the present invention being formed of parts novelly arranged in a manner which will permit said parts to discharge the functions heretofore performed by storm sashes and venetian blinds.

Still another object of importance is to provide a window construction as stated which will be quite inexpensive, and will be capable of installation at minimum costs and with maximum speed and ease.

A further object of the invention is to provide a window construction wherein, in a single unitary assembly, there will be defined a light control device, a ventilation control device, a storm shutter, a black-out shutter, and a thermo control device. In this way, it is proposed to produce a window which will be adaptable to any of various geographical areas widely varying from one another as to climatic conditions.

Other objects will appear from the following description, the claims appended thereto, and from the annexed drawing, in which like reference characters designate like parts throughout the several views, and wherein:

Figure 1 is an elevational view of a window assembly formed in accordance with the present invention, as it appears when viewed from the interior of a building structure in which it is mounted;

Figure 2 is a vertical sectional view through said assembly, in which parts remain in elevation;

Figure 3 is an enlarged transverse part sectional view, taken substantially on line 3—3 of Figure 2;

Figure 4 is an enlarged, fragmentary, longitudinal sectional view showing the means for adjusting the slats to open and closed positions;

Figure 5 is a vertical sectional view, portions being broken away, showing a modified form of operating mechanism; and

Figure 6 is a perspective view of one of the window operators illustrated in Figure 5.

Referring to the drawings in detail, the reference numeral 10 has been applied generally to a rectangular window frame, said frame being adapted to be mounted in any suitable manner in the correspondingly sized rectangular opening 12 of a building wall 14.

In a preferred embodiment of the invention, the frame 10 includes a pair of parallel, vertically disposed side frame members 16, 18, said members being connected at their upper and lower ends by a header 20 and a sill portion 22, respectively.

Mounted upon the inner surfaces of the side frame members 16, 18, are vertically disposed pivot strips 24, said pivot strips 24 extending from top to bottom of the side frame members associated therewith.

The respective pivot strips 24 are adapted to support the slats of an inner slat assembly, shown at the left in Figure 2, said inner slat assembly being so termed due to its proximity to the interior of the building wall 14.

Formed in each of the strips 24 is a longitudinal series of spaced openings 26 (Figure 3), said openings receiving trunnions 28 formed upon the opposite ends of a plurality of slats 32, said slats being horizontally dis-

posed across the window opening and being spaced vertically of one another.

It will be seen that each slat 32 is thus connected intermediate its ends to the strips 24 for movement from the horizontal position to a vertical position.

In the preferred embodiment of the invention illustrated in the drawings, the trunnions 28 can be formed upon the mid-length portions of clips 30, the respective clips 30 engaging opposite ends of each slat 32.

It should be further noted at this point that the slats of the inner slat assembly are preferably formed of glass material or the like, although it is not critical to the invention that they be so formed.

For the purpose of limiting pivotal movement of the several slats in one direction, an upper stop 34 is provided (Figures 1 and 2), said stop being formed as a long strip of material extending from the side frame member 16 to the side frame member 18, this strip being fixedly secured in any suitable manner to the underside of the header 20. It will be noted that this strip will engage the uppermost slat 30, when said slat is rotated counterclockwise from the position thereof shown in Figure 2. In this connection, when the slats of the inner slat assembly are so rotated, they overlap with one another, and thus the engagement of the top slat by the strip 34 will result in all the slats being engaged by the slats immediately thereabove.

A lower stop 36 is also provided, said lower stop extending between the members 16, 18 and being secured to the sill portion 22 of the frame, the lower stop engaging the slats when the slats are rotated clockwise from the positions thereof shown in Figure 2.

Positioned along the side member 16 and spaced from the strips 24 is a vertically disposed connecting rod 38, the rod being mounted for up and down movement. One end of each of the slats 32 is likewise connected to the rod 38 for movement from the horizontal position to a vertical position. Specifically, the connections of the respective slats 32 to the rods 38 embody pivotal connections. The pivotal connections include upstanding ears 40 formed upon the several clips 30, each ear having an opening receiving a pin extending into the connecting rod 38.

It will thus be seen that on up and down movement of the connecting rod 38, the slats 30 will be all moved simultaneously to selected positions, said slats in one extreme vertical position completely closing the window opening, and in another extreme horizontal position opening the window.

An outer slat assembly is also provided in the window constituting the present invention, the outer slat assembly being shown at the right in Figure 2. This assembly is identical in all respects to the inner slat assembly, with the exception of the material of which the slats 42 thereof are formed. Preferably, the slats 42 are of wood, metal, or other opaque material. The slats 42 have clips on their opposite ends, similar to the clips 30, said clips having trunnions rotatably mounted in openings spaced longitudinally of outer pivot strips 44. A connecting rod 46 connects the several slats 42 for joint movement, the connecting rod also being mounted along the inner side of the frame member 16 in parallelism with the connecting rod 38 of the inner slat assembly.

As shown in Figure 3, the member 16 has a transversely extending recess 48, in which is mounted an operating shaft 50, said shaft 50 being mounted on the frame member 16 both for rotation and for reciprocating movement in the direction of its own length. At its inner end, the shaft 50 is received within and is guided by a socket 52 communicating with the inner side wall of recess 48. The outer end portion of the shaft 50 projects through an opening 54 communicating between the other side wall of the recess 48 and the adjacent edge of the side frame member 16.

A separate raising and lowering means is connected

to each of the connecting rods 38 and 46 and to the shaft 50. Specifically, spaced transversely of the recess 48 are arcuate depressions 56, formed in the back wall of the recess, said depressions receiving spools 58, 60. The spools 58, 60 are circumposed about the shaft 50, and as will be noted from Figure 3, the shaft 50 has, at locations spaced longitudinally thereof, non-circular portions 62, 64. The spools 58, 60 have non-circular bores adapted to complement the non-circular portions 62, 64 of the shaft, and it will be seen that on movement of the shaft to the left in Figure 3, the non-circular portion 62 will be engaged in the complementary bore of spool 58. On movement of the shaft 50 in an opposite direction, to the right in Figure 3, the non-circular portion 64 will be engaged in the complementary bore of spool 60. It is to be noted that the non-circular portions 62 and 64 on the shaft 50 constitute a pair of clutching elements, and that the non-circular bores in the spools 58 and 60 constitute the complementary clutch elements for coaction with the aforementioned clutching elements.

Movement of the shaft 50 in the direction of its length, to an intermediate position, will cause engagement of both non-circular portions 62 and 64 in the bores of their associated spools 58, 60 respectively, thus to cause joint rotation of both spools with the shaft.

The construction is one which permits each spool to be engaged with the shaft 50 for rotation with the shaft, independently of the other spool. The construction is also one which permits both spools to be engaged simultaneously with the shaft 50, for joint rotation.

It will be understood that ordinarily, the spools 58, 60 can rotate relative to the shaft 50, when the non-circular portions of the shaft are out of engagement with the bores associated therewith.

Wound about the spool 60 is the intermediate portion of a cord 66 or other flexible element, and wound about the spool 58 is a second cord 68.

The opposite ends of cord 66 are connected to the rod 38, at locations spaced longitudinally of the rod, and therefore, on rotation of the shaft 50 with the spool 60 engaged with the shaft for rotation therewith, the connecting rod 38 will be moved upwardly or downwardly, depending upon the direction in which the shaft 50 is rotated. The same is true of the connecting rod 46.

In this way, means is provided for opening or closing the two slat assemblies, independently of or conjointly with one another. Both assemblies can be therefore adjusted to a full open position. Both assemblies, further, can be adjusted to a fully closed position. Further, the inner slat assembly can be opened to a selected extent while the outer slat assembly is fully open. Similarly, the outer slat assembly can be fully or partially opened while the inner slat assembly is fully closed. Other selected arrangements can be employed as desired, utilizing the operating mechanism shown in Figure 3.

Advantageously, the operating mechanism permits the window to have great versatility, so as to permit the window to be used as a black-out shutter, storm sash, and in other ways now possible only by the use of extraneous mechanical aids. Also, the window controls ventilation, and controls the admission of light, with the light and ventilation being regulated either independently of or conjointly with one another.

It is desirable that means be provided for locking the shaft 50 in selected positions to which it is rotated, and to this end, a bracket 70 is mounted upon the inner edge of the side frame member 16, the shaft being rotatably journaled in a block 72 provided in said bracket. The block 72 has, at its outer end, longitudinally aligned locking slots 74 disposed radially of the shaft 50, said slots being adapted to engage against rotation a turning knob 76 secured to the shaft, the turning knob having locking ribs or projections 78 complementing the slots 74. The projections 78 on the knob 76 carried by the shaft 50 and the slots 74 formed in the block 72 supported in the

bracket 70 carried by the side member 16 constitute interengaging means.

When the elements 78 are engaged in the slots 74, the non-circular portions 62, 64 of the shaft will be engaged in their associated bores, and thus both spools and the shaft will be held in selected positions to which they are adjusted.

In Figures 5 and 6 there is illustrated a modified form of the invention, wherein the operating mechanism comprises two shafts instead of one shaft. In this form of the invention, an angle bracket 80 is secured to the inner surface of the member 16, the bracket 80 having an end wall 82 formed with a non-circular aperture 84 adapted for engagement therein of a locking projection 86 formed on the inner end of a knob 88 rigid with shaft 90. It is to be noted that the aperture 84 formed in the end wall 82 of the bracket 80 carried by the side member 16 and the projection 86 formed on the knob 88 carried by the shaft 90 constitute an inter-engaging means. The shaft 90 is journaled at its inner end, in the opposite legs of a U-shaped spool housing 92 secured fixedly to the bracket 80, the bight of the spool housing having an opening 94 in which is positioned a spool 96 secured fixedly to the shaft 90 for rotation therewith. A cord 98 is wound about the spool 96 and is connected to the connecting rod 38 of the inner slat assembly in the same manner as the cord 66 in the first form of the invention.

Referring to Figure 5, a second angle bracket 100 is positioned above the angle bracket 80, and has an end wall similar to the end wall 82 of bracket 80, a knob 102 being lockingly engageable with the end wall of bracket 100. The knob 102 is fixed to a shaft 104 journaled in a bracket or spool housing spaced from the bracket 100, a spool 106 being secured to the shaft 104 for rotation therewith and having a cord 108 wound thereabout.

The cord 108 is connected to the connecting rod 46, and it will thus be seen that either knob 88 or knob 102 can be rotated by a user, to adjust the slats of the inner and outer slat assemblies as desired. Each slat assembly can, of course, be locked in a selected position to which it is adjusted, by the means described above.

The housing in which the spool 106 is positioned has been designated by the reference numeral 110, and is secured to the frame member 16 in any suitable manner, the housing 110 being of U-shaped formation, with an opening in its bight receiving the spool 106.

In both forms of the invention, the net results which may be accomplished are the same, it being readily perceived that the window constitutes a single, unitary assembly which can be manufactured and installed by a single person or firm. This unitary assembly, when installed in the window opening of a building wall, takes the place of a conventional window, and also takes the place of the several extraneous aids commonly associated with a window for the purpose of controlling light and ventilation, providing privacy, and protecting the interior of the building structure against storms.

At the same time, the window formed in accordance with the present invention can be manufactured at relatively low cost, considering the benefits to be obtained from the use thereof, and requires no special framing.

Still further, the window is so formed as to reduce to a minimum the number of frictionally engaged parts, thus to lower to a substantial degree the repair and maintenance costs usually associated with conventional windows.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor

change in construction that may be permitted within the scope of the appended claims.

What is claimed is:

1. A window construction comprising upstanding side members, a header connecting the upper ends of said side members, a sill connecting the lower ends of said side members, a pair of vertically disposed slat assemblies arranged in tandem spaced relation between said side members, each of said assemblies embodying a pair of strips extending in parallel spaced relation between said side members and fixedly secured at their upper and lower ends to said header and sill respectively, a vertically disposed connecting rod positioned along one of said side members and spaced from said strips and mounted for up and down movement, a plurality of horizontally disposed slats arranged in superimposed spaced relation between said strips and each connected intermediate its ends to said strips for movement from the horizontal position to a vertical position and connected at one end to said connecting rod for movement from the horizontal position to a vertical position, a horizontally disposed operating shaft extending transversely of said one of said side members and rotatably supported in said one of said side members, a separate raising and lowering means connected to each of said connecting rods, and means operatively connecting said shaft to both of said means for effecting the up and down movements of said connecting rods individually or collectively in response to the rotary movement of said shaft.

2. A window construction comprising upstanding side members, a header connecting the upper ends of said side members, a sill connecting the lower ends of said side members, a pair of vertically disposed slat assemblies arranged in tandem spaced relation between said side members, each of said assemblies embodying a pair of strips extending in parallel spaced relation between said side members and fixedly secured at their upper and lower ends to said header and sill respectively, a vertically disposed connecting rod positioned along one of said side members and spaced from said strips and mounted for up and down movement, a plurality of horizontally disposed slats arranged in superimposed spaced relation between said strips and each connected intermediate its ends to said strips for movement from the horizontal position to a vertical position and connected at one end to said connecting rod for movement from the horizontal position to a vertical position, a horizontally disposed operating shaft extending transversely of said one of said side members and connected to said one of said side members for rotary and reciprocatory movements, a separate raising and lowering means connected to each of said connecting rods and to said shaft, and a pair of clutching elements on said shaft arranged in spaced relation therewith and normally in coacting relation with complementary clutching elements included in each of said means for simultaneously effecting the up and down movements of both of said connecting rods in response to the rotary movement of said shaft, one of said clutching elements coacting with the complementary clutching element formed on one of said means upon reciprocatory movement of said shaft in one direction and effecting the up and down movement of only one of said connecting rods in response to rotary movement of said shaft, and the other of said clutching elements coacting with the complementary clutching element formed on the other of said means upon reciprocatory movement of said shaft in the opposite direction and effecting the up and down movement of only the other of said connecting rods in response to rotary movement of said shaft.
